United States Patent Office.

H. ZAHN, OF SAN FRANCISCO, CALIFORNIA.

Letters Patent No. 97,848, dated December 14, 1869.

CANDLESTICK.

The Schedule referred to in these Letters Patent and making part of the same.

To all whom it may concern:

Be it known that I, H. ZAHN, of San Francisco, in the county of San Francisco, and State of California, have invented a new and useful Improvement in Candlesticks; and I do hereby declare that the following is a full, clear, and exact description thereof, which will enable others skilled in the art to make and use the same, reference being had to the accompanying drawing, forming part of this specification.

This invention relates to a new and useful improvement in candlesticks, and consists in the use of a thumb-screw, in combination with the candlestick-tube, whereby the candle is kept steady and in a perpendicular position in the stick, and firmly held without the use of springs or other attachment, as will be hereinafter more fully described.

The accompanying drawing represents a view of a candlestick with my screw applied.

Similar letters of reference indicate corresponding parts.

A is the tube or barrel of the candlestick.

B is the base.

C is the slide, upon which the candle rests in the stick.

D represents the screw, which I apply for holding and steadyng the candle.

E is a screw-nut, which is riveted or soldered to the side of the tube A, as seen in the drawing. This nut is of sufficient size to admit and support the screw.

The end of the screw passes through an orifice in the tube, and is brought in contact with the candle.

By turning the screw in when the candle is in the tube, the candle may be held perfectly steady, and without the possibility of its dropping out when carried about the house, and in a perpendicular position, so that it will not be likely to flare or melt away on one side faster than on the other.

Having thus described my invention,

I claim as new, and desire to secure by Letters Patent—

In combination with a candlestick, the screw D, arranged and operating substantially as and for the purposes described.

H. ZAHN.
